Application April 19, 1950, Serial No. 156,889

16 Claims. (Cl. 1-49)

1

This invention relates to plier type hand staplers.

An object of this invention is to provide a plier type stapler of the character described comprising a pair of body members pivoted together scissors fashion, one body member having a lower anvil supporting jaw at one end and a top handle at the opposite end, and the other body member comprising an upper driver supporting jaw at one end and a lower handle at the other end, the arrangement being such that when the two handles are squeezed together the driver supporting jaw and the anvil supporting jaw move relatively towards one another, a staple magazine being disposed between said body members and pivoted thereto on their common pivot, the arrangement being such further, that when the handles are squeezed together the driver on the driver supporting jaw will eject a staple from the forward end of the staple magazine and press it against the anvil on the anvil supporting jaw.

Another object of this invention is to provide in a stapler of the character described, a staple magazine comprising an elongated staple magazine body pivoted on a common pivot to the interpivoted frame body members, an elongated staple guide within said staple magazine body attached to said body by a rivet which also fastens to the underside of the staple magazine body, a spring having two ends, one end being received within the anvil supporting jaw on one of the frame body members to urge pivotal movement between the staple magazine and the frame body which carries the anvil, and the other end of the spring being interposed between the staple magazine and the handle portion of the frame body which carries the driver, to urge pivotal movement between said magazine and last mentioned frame body.

Another object of this invention is to provide in a stapler of the character described a pair of hollow frame body members, one received within the other in crossing scissors fashion, and interpivoted on a pivot pin, and a staple magazine within said frame body members, said staple magazine comprising a staple magazine body having a bottom wall and side walls extending upwardly therefrom, and said side walls having integral downwardly extending ears formed with openings through which the pivot pin passes for pivotally connecting the staple magazine to the frame body members.

Still a further object of this invention is to provide a plier type stapler of the character described comprising a pair of crossing frame

2

body members interpivoted scissors fashion, one frame body member comprising a top handle portion from which extend downwardly, side walls, and extending from said side walls are forwardly extending side walls, provided with inwardly extending bottom flanges having meeting edges forming a support for an anvil, and an anvil riveted to said flanges and interconnecting the same to prevent said frame body member from opening up, and the second frame body member comprising a driver supporting portion having a top wall and side walls extending downwardly from the top wall and received within the side walls of the first frame body member, said side walls extending rearwardly and being formed with bottom inwardly extending flanges having meeting edges and forming a bottom handle, and a rivet interconnecting the side walls of said last mentioned handle to prevent said last mentioned frame body member from opening up, and a pivot pin extending through the overlapping side walls of said frame body members to interpivot said members scissors fashion.

25 Another object of this invention is to provide in a stapler of the character described a staple magazine comprising a staple magazine body having a bottom wall, side walls extending upwardly therefrom and flanges extending inwardly from the upper ends of the side walls, and a staple guide or core within the staple magazine body and comprising side walls spaced inwardly from the side walls of the magazine body and a top wall interconnecting the side walls of said guide and spaced below the flanges of said magazine body, and means to attach said guide to said body, whereby staples may ride on said guide, and a staple pusher comprising a pusher rod, means to detachably attach the rear end of said rod to the rear end of said magazine, said rod being disposed parallel to and spaced above the magazine body, and a pusher member slidably mounted on the pusher guide and comprising a top wall contacting the top wall of the guide and side walls contacting the side walls of said guide, said guide terminating short of the front end of the magazine body and forming a passage therewith, a member pivoted relative to the magazine and a driver fixed to said member and being movable through said passage for ejecting a staple from said passage, said pusher member including a plurality of upwardly extending apertured ears through which said pusher rod passes, spring means being mounted on said pusher rod to urge the pusher member forwardly, the forward end of said pusher rod

being flattened, the foremost ear having an opening large enough to permit the flattened portion of the rod to pass rearwardly therethrough to engage the next ear on said pusher member, and said forwardmost ear on the pusher member being adapted to engage the rear surface of the driver to limit forward movement of the pusher member after the last staple on the magazine has entered said passage, and to prevent the pusher member from moving to a position beneath the driver.

Yet another object of this invention is to provide in a stapler of the character described a staple magazine comprising a magazine body having a bottom wall and side walls and inwardly extending flanges at the upper ends of the side walls, a staple guide fixed within the magazine body, a staple pusher comprising a pusher rod, a pusher member slidable on the rod, a member fixed to the rear end of the rod and having a U-shaped or bent back portion insertable between the staple guide and the bottom wall of the staple body, the bottom wall of the staple body being formed with an opening and a projection on said U-shaped portion adapted to engage within said opening to releasably latch the rear end of the pusher rod relative to the staple magazine, and a finger extending downwardly from said U-shaped portion to permit the operator to press upwardly on the finger to release said projection from said opening, whereby to permit the staple pusher to be removed rearwardly from the magazine.

Yet a further object of this invention is to provide a strong, rugged and durable plier type stapler of the character described, which shall be relatively inexpensive to manufacture, which shall be easy to manipulate, and which shall yet be practical and efficient to a high degree in use.

Other objects of this invention will in part be obvious and in part hereinafter pointed out.

The invention accordingly consists in the features of construction, combination of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a top plan view of a plier type stapler embodying the invention;

Fig. 2 is a cross-sectional view taken on line 2-2 of Fig. 1;

Fig. 3 is a view substantially similar to Fig. 2 but showing the handles squeezed together to a degree;

Fig. 4 is an enlarged rear end view of the staple pusher device;

Fig. 5 is a partial view taken on line 5-5 of Fig. 2;

Fig. 6 is an enlarged cross-section view taken on line 6-6 of Fig. 3;

Fig. 7 is a cross-sectional view taken on line 7-7 of Fig. 3;

Fig. 8 is a front end view of the staple magazine;

Fig. 9 is a side elevational view of the staple magazine in its full elevated position;

Fig. 10 is a bottom plan view of the staple magazine;

Fig. 11 is a side elevational view of the staple pusher device;

Fig. 12 is a bottom plan view of the staple magazine;

Fig. 13 is a transverse cross-sectional view of the anvil taken on line 13-13 of Fig. 5; and

Fig. 14 is a cross-sectional view taken on line 14-14 of Fig. 11.

Referring now in detail to the drawing, 10 designates a stapler embodying the invention. The same comprises generally an anvil frame body member 11 pivoted to a driver frame body member 12 on a pivot pin 13 to which there is also pivoted a staple magazine 14.

The anvil frame body member 11 (Fig. 2) may be made of sheet metal and comprises a top transversely and longitudinally curved wall 16 having a forward edge 17 (Fig. 3). The wall 15 16 is formed with an inwardly curved portion 18 at its outer end. Extending from the top wall 16 are integral parallel side walls 19 having lower edges 20 extending upwardly to the rear edge 21 of the portion 18. Extending from the 20 side walls 19 and disposed in the plane thereof and extending forwardly and downwardly are portions 23. The portions 23 have curved forward front edges 24 extending upwardly to the front edge 17 of the top wall 16. Said side wall 25 portions 23 have downwardly and forwardly inclined rear edges 25 curved forwardly at their lower ends as at 26. Extending forwardly from the side wall portions 23 are parallel side or jaw portions 27 having upper edges 28 extending rearwardly to the lower ends of the edges 24. Extending inwardly from the lower ends of the side walls 27 are coplanar bottom flanges 29 inclined forwardly and upwardly relative to the edges 28. Extending upwardly from the bottom flanges 29 are front flanges 30 having upper edges 31 in the plane of the edges 28. Extending upwardly from the rear ends of the bottom flanges 29 are shoulders 32 from which extend upwardly and rearwardly, curved tongues 33 for the purpose hereinafter appearing. The center of curvature of tongues 33 is the axis of pivot pin 13.

The side walls 23 are formed with through openings 34 through which the pivot pin 13 passes, the outer ends of said pivot pin being riveted over, as at 35, against the outer surfaces of the side walls 23. It will be noted that the through openings 34 and the pivot pin 13 are located just above the level of the edges 28 as shown in the drawing and are also located between the edges 24 and 25 of member 11. It will now be understood that portions 16, 18 and 19 of member 11 constitute a top handle H, whereas the portions 27, 29 and 30 constitute a bottom jar J for supporting an anvil 36, as will appear hereinafter. It will be noted that member 11 is made of a single piece of stamped sheet metal.

The frame body member 12 is also made of a single piece of stamped sheet metal. The same comprises a top wall 40 at the rear end of which is a downwardly extending shoulder 41 contacted by the front edge 17 of wall 16. Extending rearwardly from the shoulder 41 is a curved portion 42 having a curvature the center of which is the axis of the rivet 13. Extending from the top wall 40 are front parallel side walls 43, and extending downwardly from the forward end of top wall 40 is a wall 44 the edges of which contact the inner surface of the side walls 43. The walls 40, 43 and 44 constitute an upper jaw J' of the stapler as will appear hereinafter.

Extending downwardly and rearwardly from the side walls 43 are wall portions 45 in the same plane with the walls 43 and contacting the

inner surfaces of walls 23 of member 11. Walls 45 have upper edges 46 curved downwardly and rearwardly, and lower edges 47 curved downwardly and rearwardly substantially to the location of the shoulder 32 of member 11, when the stapler is in normal position.

Extending downwardly and rearwardly from the side wall portions 45 are side wall portions 48. Said side wall portions 48 have upper edges 49 merging at their front ends with the edges 46. Extending downwardly and rearwardly from the rear ends of edges 49 are inclined edges 50 from which there extends downwardly rear vertical edges 51. Extending inwardly from the lower ends of the side walls 48 are flanges 52 having meeting edges. At the front ends of the flanges 52 are edges 53 contacting the shoulders 32 when the stapler is in normal position. At the rear ends of the flanges 52 are upwardly curved flange portions 55.

It will now be understood that the portions 48, 52, 55 of frame member 12 constitute a lower handle H'. It will also be understood that when the handles H, H' are squeezed together the jaws J, J' will move together and that when the handles H, H' move apart, the jaws J, J' will separate. When the handles H, H' are squeezed together, edges 17 and 53 move away from the shoulders 41 and 32 respectively but the spaces therebetween will in such event be covered by the curved portions 42 and 33 respectively.

The flanges 29 are each formed with an upwardly pressed boss or bump 60 having a flat top surface 61 parallel to the edges 28. The bumps 60 are in alignment with each other. The anvil 36 comprises a plate 62 which fits in between the side walls 27 and contacts the inner surfaces of portions 30 with the top surface of plate 62 in the plane of the edges 28, 31. It will be noted that the side walls 27 have notches 27a at their forward ends to receive wings 62a of the plate 62. Also, the upwardly extending tongues 30 are notched at their outer sides to receive said wings, thereby preventing side or end shifting of the plate. The plate 62 is formed with a pair of downwardly depressed bumps 64 resting upon the bumps 60. The bumps 60, 64 are formed with registering through openings receiving rivets 65 for riveting the anvil plate 62 to the flanges 29 and thereby interconnecting said flanges and preventing the handle member 11 from opening up at the split formed by the meeting edges of the flanges 29. It will be noted that while the flanges 29 are inclined upwardly and forwardly the meeting surfaces of the bumps 64 and 60 are in a plane parallel to the plane of the edges 28, 31, so as to retain the anvil plate 62 in the plane of said edges.

The upper surface of the anvil plate 62 is formed adjacent its front end with the usual anvil slot 66 for clinching the legs of the staples inwardly when the stapler is used. The bumps 60, 64 provide spaces in the heads of the rivets 65 as shown more particularly in Fig. 2 of the drawing.

The walls 48 are interconnected by a transverse pin 68 riveted over at its ends and passing through suitable openings in said walls. The pin 68 is located adjacent the upwardly curved flange portions 55. Said rivet or pin 68 serves to prevent the side walls of the frame member 12 from separating and it also has a further function which will appear hereinafter.

The top wall 40 of jaw J' is formed with a

through opening 69, and extending therethrough is a rivet 10 which serves to fix one end 71 of a driver member 72 to the underside of said wall. Said end portion 71 contacts the underside of wall 40 and is formed with an apertured or hole registering with the hole 69. Member 72 may be made of spring steel and it has a portion 74 inclined downwardly and forwardly and being longitudinally curved. The radius of curvature of said portion 74 is the axis of the rivet 13. The lower end of said portion 74 is somewhat below the lower edge 44a of tongue 44 and is spaced rearwardly from said tongue. The purpose of the driver blade 74 will be apparent as the description of the stapler proceeds.

The staple magazine 14 is pivoted to the pivot pin 13 as shown in the drawing. Said staple magazine 14 comprises a magazine body or housing 75 having a flat bottom wall 76 from which extend upwardly side walls 77. Extending inwardly from the upper ends of the side walls 77 are top flanges 78, the inner edges of which are spaced from one another forming a slot 79 therebetween. The bottom wall 76 has a rear edge 80. The rear corners of the bottom wall 76 are cut away to form a rear central tongue 81 having side edges 82 extending to a pair of aligned shoulders or side end edges 83. Said bottom wall is furthermore formed with rectangular central opening 84, the major portion of which is disposed within the tongue 81. Said bottom wall 76 is furthermore formed with an intermediate cut away portion 85 forming parallel transverse edges 86 and 87. The metal between the edges 86 and 87 is split along the longitudinal midsection and pressed downwardly into the plane of the side walls 77 and rounded off to form ears 88, apertured as at 89 and through which the pivot pin 13 passes. The axis of the openings 89 in the ears is somewhat below the plane of the underside of the bottom wall 76.

The bottom wall 76 is furthermore formed for the purpose hereinafter appearing, adjacent the edge 86 (Fig. 12) with a through opening 90 located on the longitudinal midsection of the housing 75. At the forward end of the bottom wall 76 is a front edge 91. The front corners of the bottom wall 76 are cut away to form a central tongue 92 at the front end having side edges 93 extending to front side edges or shoulders 94. The side walls 77 of the staple housing have rear edges 95 in the plane of the rear edges 83. Said side walls 77 furthermore have upwardly and forwardly inclined edges 96 extending from the rear edges 95 to the top flanges 78. At the front end of the housing the side walls extend forwardly of the shoulders 94, as at 96. The lower edges of portion 96 extend down to the plane of the underside of bottom wall 76. Between the portions 96 and edges 94, however, the side walls 77 are formed with notches 97. Extending from the front ends of said wall portions 96 are front wall portions 98 disposed in one plane and having meeting edges 99. The lower edges of the front walls 98 are in the plane of the lower edges of side walls 96 and hence likewise in the plane of the undersurface of the bottom wall 76 of the magazine housing. The upper ends of walls 98 are just rear of the lower end of tongue 44.

Disposed within the magazine housing 75 is a staple guide or core 100 provided with a top wall 101 spaced below the flange 78 and extending downwardly from said top wall 101 are side

walls 102 spaced inwardly from the side walls 77 of the housing. The lower edges of member 100 contact the upper surface of the bottom wall 76. A staple strip may ride on member 100 with the crowns of the staple resting on the top wall 101 and beneath flanges 78 and with the legs of the staple strip in the space between the walls 102 and 77. The top wall 101 is formed with a downwardly depressed boss 103 having a central opening through which extends a rivet 104 which passes likewise through the opening 90 for attaching the core or guide 100 to the housing 75. The upper head of the rivet is received within the recess bump 103 so that the staple strip may ride over the rivet.

The rear ends of the top of side walls of the guide 100 are in a vertical plane passing through the edge 80 of the bottom wall 76. Said side walls 102 are formed with downwardly extending tongues 105 contacting the side edges 82 of the tongue 81, with the inner ends of the tongues 105 contacting the shoulders 83. The lower end edges of the tongues 105 are in a plane of the undersurface of the bottom wall 76.

At the forward edges of the side walls 102 are likewise a pair of tongues 106 contacting the side edges 93 of the tongue 92. The rear ends of the tongues 106 contact the shoulders 94. The lower edges of the tongues 106 are in the plane of the undersurface of the bottom wall 76. The front ends of the side walls 102 and the front end of the top wall 101 are in a common plane spaced somewhat rearwardly from the inner surfaces of the front wall portions 98, forming therewith a passage of a width sufficient for a staple to be driven downwardly therethrough against the anvil. It will now be understood that side movement or end movement of the guide 100 relative to the staple housing is prevented due to the engagement of tongues 105 and 106 with the tongues 80 and 92 and with the shoulders 83 and 94 respectively.

It will be observed that the front walls 98 extend above the flanges 78. It will also be observed that the lower end of the driver blade 14 contacts the inner surfaces of the upper ends of said front walls 98. When the handles are squeezed the jaws J' and J move closer to each other and the blade enters the passage P between the front end of the staple guide and the front walls 98 to expel or depress a staple through said passage against the anvil for a stapling operation.

It will be noted that the rivet 104 is spaced rearwardly of the pivot pin 13 and that the staple magazine 14 may be rotated in a clockwise direction relative to the frame body member 12. Normally the major portion of the rear end of the staple magazine projects above the edges 49 of the frame body 12 and the forward end of the staple magazine projects below the upper jaw J' of said frame body 12.

Spring means is provided to return frame body members 11 and 12 and the magazine body to the normal inoperative position, shown in Figs. 2 and 9. To this end there is attached to the underside of the staple magazine body by means of said rivet 104 a spring S. The spring S has an intermediate portion 110 contacting the portion of the bottom wall 76 just rearwardly of the edge 86. It is formed with a through opening through which the rivet 104 passes, said rivet having a head at its underside contacting the underside of said portion 110. Thus the single rivet 104 serves to attach the spring S to the

staple magazine as well as serving to attach the staple guide to the staple housing.

Extending rearwardly from the intermediate portion 110 is a rearwardly and downwardly inclined spring tongue 111 having an upwardly bent end 112 contacting the upper side of the connecting pin 68. Extending forwardly from the intermediate portion 110 is a downwardly inclined spring portion 113 having an upwardly turned end portion 114 contacting the upper surfaces of the bottom flanges 29. When the handles H, H' are first squeezed from the position shown in Figs. 2 and 9, the bottom jaw J moves upwardly toward the front end of the staple magazine. During this operation the staple magazine turns slightly in a counterclockwise direction relative to the upper jaw J'. Continued squeezing action of the handles after the lower jaw J, with the work to be stapled thereon, contacts the forward end of the staple magazine, will cause the lower jaw, together with the staple magazine, to move in a clockwise direction relative to the upper jaw, to cause a staple to be ejected for stapling the work. Upon release of pressure from the handles H, H', the handles and the staple magazine are moved back to normal position by the spring S. Thus, during the first part of the squeezing operation of the handles the forward end 113 of the spring is tensioned by movement of the lower jaw J upwardly towards the upper jaw J'. During the remainder of the squeezing operation the rear end 111 of the spring is tensioned since the rear end of the staple magazine moves in a clockwise direction relative to the lower handle H'.

Mounted on the staple magazine is a pusher mechanism 120 for advancing a staple strip within the magazine. Said mechanism 120 comprises a pusher rod 121 having at its front end a flattened and widened part 122. Riveted or otherwise attached to the rear end of the pusher rod 121 is a latching member 123. Said latching member 123 comprises a vertical wall 124 formed with an opening to receive the rear end of the rod, said rear end being riveted to the wall 124 at 125. The wall 125 extends below the pusher rod 121, and extending from the lower end of said wall is a wall 126 parallel to and disposed below the rod. Extending from wall 126 is a bent back portion 127 from which there extends a portion 128 disposed parallel to and below the wall 126. Extending downwardly from the rear end of wall 128 is a vertical wall 129 in the plane of wall 124. Pressed downwardly from the rear end of wall 126 is a lug 130. Cut from wall 128 is a downwardly and rearwardly inclined tongue 131.

Slidably mounted on the rod 121 is a pusher member 132 which may be made from a single piece of die cut and stamped sheet metal. The pusher member 132 has a top wall 133 which contacts the top wall 131 of the guide 100. Extending downwardly from the sides of the top wall 133 are side walls 134 which contact the outer surfaces of side walls 102.

Extending upwardly from the front end of top wall 133 is an ear 135 formed with a central opening 136 of sufficient diameter that the flattened part or tongue 122 may readily pass therethrough. Cut from the top wall 133 and extending upwardly therefrom is an ear 137 parallel to ear 135 and formed with an opening 138 sufficiently large to permit the push rod 121 to be slidably moved therethrough, but of smaller diameter than the width of the flattened tongue 122, so that the ear 137 will limit rearward movement of

the push rod 121, due to contact of the flattened tongue 122 with said ear.

Also cut from the top wall 133, and extending upwardly therefrom is an ear 140 similar to ear 137 and formed with an opening 141 of the same size as opening 128 and likewise permitting the push rod 121 to be slidably moved therethrough. On push rod 121 and between ear 140 and wall 124 is a coil compression spring 142. It will now be understood that in use the push member 132 is slidably mounted on the guide 100. The push rod 121 is disposed above and in parallel relationship to the staple magazine housing. The U-shaped portion 126, 127 and 128 is of such size that it can be inserted into the staple guide 100 so as to be disposed between the guide and the bottom wall of the housing. The tongue 131 will snap into the opening 84 so as to engage the rear edge 84a of said opening to releasably latch the pusher mechanism to the magazine.

The spring 142 urges the pusher member 132 forwardly to advance the staple strip within the magazine. When the last staple of a staple strip has been ejected, the upper end of the ear 135 will contact the rear surface of the lower end of the driver blade 74 to stop further forward movement of the pusher member 132. With such construction it is not possible for the pusher member to move beneath the driver blade. When it is desired to place a new staple strip in the magazine, member 129 is pushed upwardly to release the tongue 131 from the opening 84. The entire pusher mechanism 120 may then be moved rearwardly from the magazine. A staple strip may then be inserted through the rear end of the magazine. The pusher mechanism may then be reinserted and pushed forwardly until the tongue 131 again latches against the edge 84a. The bump 130 limits upwardly movement of wall 128 toward wall 126.

It will be observed that the pivot pin 13 is located above the portion 113 of the spring. If it were attempted to rotate the staple magazine in a counterclockwise direction relative to the frame body member 11, the pivot pin 13 pressing on the spring portion 113 between the outer end 114 thereof, and the intermediate attached portion 110, would prevent such movement so as to make sure that the front walls 98 of the magazine did not move below the lower end 44a of the front wall 44, and also to make sure that contact is not lost between the driver blade 74 and the inner surface of the upper end of said front walls 98.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A plier type hand stapler comprising a pair of interpivoted and interfitting frame body members having forward jaw portions, intermediate crossing portions, and rearwardly extending handle portions, and a staple magazine between said frame body members and pivoted thereto on a common pivot, and a spring attached to the magazine at a point spaced from the common

pivot and having one end engaging the jaw of one body member and the handle of the other body member.

2. A plier type hand stapler comprising a pair of interpivoted and interfitting frame body members having forward jaw portions, intermediate crossing portions, and rearwardly extending handle portions, and a staple magazine between said frame body members and pivoted thereto on a common pivot, and a spring attached to the magazine at a point spaced from the common pivot and having one end engaging the jaw of one body member and the handle of the other body member, said staple magazine comprising a staple body, a staple guide within said body, and the means for attaching the spring to the magazine serving also to attach the magazine body to the magazine guide.

3. A plier type hand stapler comprising a pair of frame body members interpivoted scissors fashion by a pivot pin, one frame member having an upper forwardly extending jaw and a lower rearwardly extending handle and an interconnecting crossing portion, and the other frame body member having a lower forwardly extending jaw and an upper rearwardly extending handle and a crossing interconnecting portion, and a staple magazine pivoted to said frame body members on their common pivot, and a spring attached to the underside of the magazine and having a forwardly extending free end portion engaging said lower jaw, and a rearwardly extending free end portion engaging the lower handle.

4. An plier type hand stapler comprising a pair of frame body members interpivoted scissors fashion by a pivot pin, one frame member having an upper forwardly extending jaw and a lower rearwardly extending handle and an interconnecting crossing portion, and the other frame body member having a lower forwardly extending jaw and an upper rearwardly extending handle and a crossing interconnection portion, and a staple magazine pivoted to said frame body members on their common pivot, and a spring attached to the underside of the magazine and having a forwardly extending free end portion engaging said lower jaw, and a rearwardly extending free end portion engaging the lower handle, the point of attachment of the spring to the staple magazine being disposed rearwardly of the common pivot of the frame body members and the staple magazine.

5. A plier type hand stapler comprising a pair of interpivoted frame body members, one member comprising a lower forwardly extending jaw and an upper rearwardly extending handle and an interconnecting crossing portion, the other frame body member comprising an upper forwardly extending jaw and a lower rearwardly extending handle and an interconnecting crossing portion, a pivot pin passing through openings in said crossing portions to interpivot said frame body members scissors fashion, a staple magazine within and between said frame body members and comprising a magazine body having openings through which said pivot pin passes for pivotally connecting the staple magazine to said body frame members, a staple guide within said magazine body, means for attaching the guide to the magazine body, and a spring having an intermediate portion attached to the underside of the magazine body by the means which attaches the body to the staple guide, and said spring having a forwardly extending free end portion engag-

ing the lower jaw, and a rearwardly extending free end portion engaging the lower handle.

6. A plier type hand stapler comprising a pair of interpivoted frame body members, one member comprising a lower forwardly extending jaw and an upper rearwardly extending handle and an interconnecting crossing portion, the other frame body member comprising an upper forwardly extending jaw and a lower rearwardly extending handle and an interconnecting crossing portion, a pivot pin passing through openings in said crossing portions to interpivot said frame body members scissors fashion, a staple magazine within and between said frame body members and comprising a magazine body having openings through which said pivot pin passes for pivotally connecting the staple magazine to said body frame members, a staple guide within said magazine body, means for attaching the guide to the magazine body, and a spring having an intermediate portion attached to the underside of the magazine body by the means which attaches the body to the staple guide, and said spring having a forwardly extending free end portion engaging the lower jaw, and a rearwardly extending free end portion engaging the lower handle, the means which attaches the staple guide and the spring to the staple magazine body being disposed rearwardly of said pivot pin.

7. A plier type hand stapler comprising a pair of interpivoted frame body members, one member comprising a lower forwardly extending jaw and an upper rearwardly extending handle and an interconnecting crossing portion, the other frame body member comprising an upper forwardly extending jaw and a lower rearwardly extending handle and an interconnecting crossing portion, a pivot pin passing through openings in said crossing portions to interpivot said frame body members scissors fashion, a staple magazine within and between said frame body members and comprising a magazine body having openings through which said pivot pin passes for pivotally connecting the staple magazine to said body frame members, a staple guide within said magazine body, means for attaching the guide to the magazine body, and a spring having an intermediate portion attached to the underside of the magazine body by the means which attaches the body to the staple guide, and said spring having a forwardly extending free end portion engaging the lower jaw, and a rearwardly extending free end portion engaging the lower handle, the means which attaches the staple guide and the spring to the staple magazine body being disposed rearwardly of said pivot pin, said pivot pin being disposed above and closely adjacent to the forwardly extending portion of said spring.

8. A plier type hand stapler comprising a pair of frame body members interpivoted scissors fashion by a pivot pin, one frame member having an upper forwardly extending jaw and a lower rearwardly extending handle, and the other frame body member having a lower forwardly extending jaw and an upper rearwardly extending handle, and a staple magazine pivoted to said frame body members on their common pivot, said upper jaw comprising a top wall and side walls and a front wall extending downwardly from the top wall, and said staple magazine having a front wall extending upwardly above the lower edge of the front wall of the upper jaw and being disposed just rearwardly of said lower end, said staple magazine having a passage in back of the

front wall thereof through which a staple may be ejected from the magazine, and a driver attached to the underside of the top wall of the upper jaw and having a blade contacting the rear surface of the upper end of the front wall of said magazine, and adapted to enter said passage to eject staples from the magazine.

9. A plier type hand stapler comprising a pair of frame body members interpivoted scissors fashion by a pivot pin, one frame member having an upper forwardly extending jaw and a lower rearwardly extending handle, and the other frame body member having a lower forwardly extending jaw and an upper rearwardly extending handle, and a staple magazine pivoted to said frame body members on their common pivot, said upper jaw comprising a top wall and side walls and a front wall extending downwardly from the top wall, and said staple magazine having a front wall extending upwardly above the lower edge of the front wall of the upper jaw and being disposed just rearwardly of said lower end, said staple magazine having a passage in back of the front wall thereof through which a staple may be ejected from the magazine, and a driver attached to the underside of the top wall of the upper jaw and having a blade contacting the rear surface of the upper end of the front wall of said magazine, and adapted to enter said passage to eject staples from the magazine, said blade being curved longitudinally, and the center of curvature thereof being the axis of the common pivot for said frame body members and magazine.

10. A plier type hand stapler comprising a frame body member having a top wall, parallel side walls extending downwardly therefrom and forming an upper handle therewith, forward and downward extensions from said side walls forming an intermediate crossing portion, portions extending forwardly from said crossing portions, and bottom flanges extending inwardly from the lower ends of said forwardly extending portions and forming a lower jaw therewith, a second frame body member comprising an upper jaw having a top wall and side walls extending downwardly from said top wall, and rearwardly and downwardly inclined extensions on said side walls forming intermediate crossing portions which cross the first mentioned crossing portions, rearward extensions extending from the crossing portions of the second frame body member having at their lower ends inwardly extending bottom flanges having meeting edges and forming with said rearward extensions a lower handle, a pivot pin passing through openings in the crossing portions of said body members and interpivoting the same scissors fashion, a staple magazine member disposed within and between said two frame body members and pivoted to said pivot pin, one end of said magazine member being in proximity to the end of said upper jaw, and unitary spring means carried by one of said three members rearwardly of said pivot pin and engaging the other two members, said spring means simultaneously urging said handle members apart and one end of said magazine member away from said upper jaw.

11. A plier type hand stapler comprising a frame body member having a top wall, parallel side walls extending downwardly therefrom and forming an upper handle therewith, forward and downward extensions from said side walls forming an intermediate crossing portion, portions extending forwardly from said crossing portions,

and bottom flanges extending inwardly from the lower ends of said forwardly extending portions and forming a lower jaw therewith, a second frame body member comprising an upper jaw having a top wall and side walls extending downwardly from said top wall, and rearwardly and downwardly inclined extensions on said side walls forming intermediate crossing portions which cross the first mentioned crossing portions, rearward extensions extending from the crossing portions of the second frame body member having at their lower ends inwardly extending bottom flanges having meeting edges and forming with said rearward extensions a lower handle, a pivot pin passing through openings in the crossing portions of said body members and interpivoting the same scissors fashion, a staple magazine disposed within and between said frame body members and pivoted to said pivot pin, a spring attached to said magazine rearwardly of the pivot and having end portions one of which engages the lower jaw and the other which engages the lower handle, said staple magazine comprising a staple body and a staple guide within said body, and the means which attaches the spring to the magazine serving to interconnect the staple body, staple guide and said spring.

12. A plier type hand stapler comprising a frame body member having an upper forwardly extending jaw, said jaw comprising a front wall, crossing portions extending from said jaw, and a lower handle extending rearwardly from said crossing portions, said crossing portions being formed with aligned openings, a second frame body member comprising a rearwardly extending upper handle, crossing portions extending downwardly from said upper handle and crossing the crossing portions of the first frame body member, and a lower jaw extending forwardly from said crossing portions of the second frame body member, the crossing portions of the second frame body member being formed with openings registering with the first mentioned openings, a pivot pin passing through said registering openings to interpivot said frame body members, an anvil plate attached to the lower jaw, a staple magazine formed with openings through which said pivot pin passes, said staple magazine being disposed within said crossing portions and between said frame body members, and said staple magazine comprising a front wall extending above and at the rear of the lower end of the front wall of the upper jaw.

13. A plier type hand stapler comprising a frame body member having an upper forwardly extending jaw, said jaw comprising a front wall, crossing portions extending from said jaw, and a lower handle extending rearwardly from said crossing portions, said crossing portions being formed with aligned openings, a second frame body member comprising a rearwardly extending upper handle, crossing portions extending downwardly from said upper handle and crossing the crossing portions of the first frame body member, and a lower jaw extending forwardly from said crossing portions of the second frame body member, the crossing portions of the second frame body member being formed with openings registering with the first mentioned openings, a pivot pin passing through said registering openings to interpivot said frame body members, an anvil plate attached to the lower jaw, a staple magazine having openings through which said pivot pin passes, said staple magazine being disposed within said crossing portions and

between said frame body members, and said staple magazine comprising a front wall extending above and at the rear of the lower end of the front wall of the upper jaw, said staple magazine being formed with a passage in back of the front wall thereof and a driver attached to the underside of the top wall of the upper jaw and having a driver blade portion contacting the inner surface of the upper end of the front wall of the staple magazine.

14. A plier type hand stapler comprising a body member having an upper forwardly extending jaw, said jaw comprising a front wall, crossing portions extending from said jaw, and a lower handle extending rearwardly from said crossing portions, said crossing portions being formed with aligned openings, a second frame body member comprising a rearwardly extending upper handle, crossing portions extending downwardly from said upper handle and crossing the crossing portions of the first frame body member, and a lower jaw extending forwardly from said crossing portions of the second frame body member, the crossing portions of the second frame body member being formed with openings registering with the first mentioned openings, a pivot pin passing through said registering openings to interpivot said frame body members, an anvil plate attached to the lower jaw, a staple magazine formed with openings through which said pivot pin passes, said staple magazine being disposed within said crossing portions and between said frame body members, and said staple magazine comprising a front wall extending above and at the rear of the lower end of the front wall of the upper jaw, said staple magazine being formed with a passage in back of the front wall thereof and a driver attached to the underside of the top wall of the upper jaw and having a driver blade portion contacting the inner surface of the upper end of the front wall of the staple magazine, and said driver blade portion being curved longitudinally and the center of curvature of said blade being at the axis of the pivot pin.

15. A plier type hand stapler comprising a body member having an upper forwardly extending jaw, crossing portions extending from said jaw, and a lower handle extending rearwardly from said crossing portions, said crossing portions being formed with aligned openings, a second frame body member comprising a rearwardly extending upper handle, crossing portions extending downwardly from said upper handle and crossing the crossing portions of the first frame body member, and a lower jaw extending forwardly from said crossing portions of the second frame body member and comprising side walls and bottom inwardly extending flanges, the crossing portions of the second frame body member being formed with openings registering with the first mentioned openings, a pivot pin passing through said registering openings to interpivot said frame body members, an anvil plate attached to the flanges of said lower jaw, a staple magazine formed with openings through which said pivot pin passes, said staple magazine being disposed within said crossing portions and between said frame body members, and a longitudinal staple guide within the staple body, the staple guide and staple magazine being formed with aligned openings, and a spring having an intermediate portion contacting the underside of the staple magazine and being formed with an opening registering with the opening therein, and a rivet 75 passing through the openings in the staple guide

and staple magazine, and in the intermediate portion of said spring, and serving to attach said magazine to the guide and spring, and said spring having a forwardly extending portion engaging the upper surfaces of the bottom flanges of the lower jaw and a rearwardly extending portion pressing down on the rearwardly extending lower handle. 5

16. A stapler according to claim 10, further comprising an anvil carried by said lower jaw, 10 said anvil being secured to both of said inwardly extending bottom flanges for holding said flanges fixedly positioned with respect to each other.

FRANK S. BOROUGH.
